United States Patent Office

Des. 196,501
Patented Oct. 8, 1963

196,501

GOLF CART

Vernon R. Kaufman, Racine, Wis., assignor to Jacobsen
Manufacturing Co., Racine, Wis., a corporation of Wisconsin

Filed Dec. 3, 1962, Ser. No. 72,691

Term of patent 14 years

(Cl. D14—3)

F 6. ■

FIG. 3

FIG. 2

FIG. 1 is a side perspective view of a golf cart embodying my new design.

FIG. 2 is a perspective view taken diagonally opposite FIG. 1.

FIG. 3 is a side perspective view of a fragment of the golf cart shown in FIGS. 1 and 2.

I claim:

The ornamental design for a golf cart, substantially as shown, and described.
